UNITED STATES PATENT OFFICE.

IRVING H. GREENE, OF NEW YORK, N. Y.

NUTCRACKER.

Application filed June 12, 1926. Serial No. 115,439.

This invention relates to nut crackers, and has for its primary object to provide a simple, effective and easily operated device for cracking various kinds of nuts and particularly hard shelled nuts without crushing or macerating the nut kernel.

More particularly, the novel feature of my present invention resides in the provision of a nut cracking device embodying two pivotally connected jaw members having their opposed nut engaging edges curved on different eccentric radii with respect to the pivot whereby, in the closing movement of the jaws upon the nut, a rolling movement is imparted to the nut during the progressively increasing compressive force which is thereby applied to the nut shell so that said force is more or less uniformly distributed upon the shell wall, resulting in the cracking or breaking of the shell at a number of different points circumferentially thereof so that said shell may be easily separated from the kernel, and then later removed in some cases whole and unbroken and in others in large sections.

A feature of the present invention is the leaf spring by means of which the jaw members are yieldingly held in expanded position.

It is a further general object of my invention to provide a nut cracker of the above character which however, is relatively simple in its construction and can be manufactured and sold at small cost.

With the above and other objects in view, the invention consists in the improved nut cracker and in the form, construction and relative arrangement of its several parts as will be hereinafter more fully described, illustrated in the accompanying drawings and subsequently incorporated in the subjoined claims.

In the drawing, wherein I have illustrated one simple and practical embodiment of the invention, and in which similar reference characters designate corresponding parts throughout the several views,

Figure 1 is an edge view of a nut cracker embodying one form of my present improvements, and

Fig. 2 is a side elevation thereof, the jaws being shown in full lines in open position and in dotted lines in their closed positions.

Referring in detail to the drawing, the device as therein shown embodies two lever

members 5 and 6 respectively, which may be of any suitable or preferred form. The lever member 5 at one of its ends is widened to form the jaw 7 while the corresponding end of the other lever member 6 is laterally curved to form the jaw 8. In the edge of the jaw 7 at the end thereof a suitably shaped recess 9 is formed to receive the apertured ear or lug 10 which projects at an angle from the extremity of the curved jaw 8 of the lever 6 and is loosely engaged for pivotal movement upon the pin 11 fixed in the jaw 7.

Preferably, I provide a suitable means for normally holding the two jaws yieldingly in open position with their toothed edges in spaced relation with each other, such for instance as the leaf spring 14 which may have a bifurcated portion to straddle the lug or ear 10, the end thereof being suitably fixed in the jaw 7 while the other end of said leaf spring bears against the inner edge of the jaw 8, and is freely slideable over the surface thereof.

In the operation of the nut cracking device above described, the nut is arranged between the toothed edges of the two jaws as shown in full lines in Fig. 2 of the drawings and the lever members 5 and 6 are forced towards each other to close said jaws upon the nut. In this closing movement of the jaws, the teeth 12 on the jaw 7 tend to urge the nut in one direction while the teeth 13 on the jaw 8 tend to urge the nut in an opposite direction. Thus, as these jaws exert a compressing action upon the shell of the nut, they also impart to said nut a bodily rolling movement between the two jaws. It is therefore, evident that the compressing pressure is not applied entirely at one point on the nut, but this pressure is more or less uniformly distributed circumferentially or tangentially around the wall of the nut shell and said shell will therefore, be cracked or broken at a number of spaced points. Therefore, the possibility of badly crushing or macerating the kernel of the nut is obviated. After the nut shell has thus been cracked, the nut is removed from between the jaws 7 and 8 and the parts of the shell may then be readily separated from the nut kernel. It will be found that the latter, in many cases, remains practically whole or unbroken. I have found the device to be particularly advantageous in the cracking of

such nuts as hard shell pecans, which as is well known, are one of the several species of nuts which are most difficult to properly crack without badly crushing the kernel. 5 It will be understood that the eccentric curvature of the opposed edges of the two nut cracking jaws is such that nuts of many different sizes may be accommodated there-between and cracked with equal ease and 10 facility.

Owing to the spring structure wherein the bifurcated ends are anchored in one of the jaws and its opposite end is freely slideable over the co-operating jaw, it will be apparent 15 that the spring will be rigidly sustained against accidental removal and cannot be readily displaced, since the legs formed by the bifurcation straddle the lug in such a manner that lateral displacement of the 20 spring is virtually impossible. Furthermore, the solid bight portion of the spring bears against the adjacent jaw thereby producing a relatively stiff body at the free disconnected end of the spring which materially strengthens the same and avoids 25 breakage or lateral displacement.

From the above description considered in connection with the accompanying drawing, it is believed that the construction, manner 30 of use and several advantages of my invention will be clearly understood. While I have referred to a particular manner of pivots connecting the two jaws with each other, it will be understood that this is not essential and that various other means 35 might be adopted for effecting this pivotal connection. Also, the several other detail parts of the device as herein described are susceptible of more or less modification in the form, proportion and relative arrangement of the several parts, and I accordingly, 40 reserve the privilege of making all such legitimate changes therein as may be fairly embodied within the spirit and scope of 45 the invention as claimed.

I claim:

1. A nut cracking device comprising two lever members, one of said members having a flattened end providing a jaw thereon and the other member having a laterally curved 50 end portion forming a complementary jaw and terminating in an angularly projecting lug, a pivot pin connecting said lug with the first named jaw, the opposed edges of said jaws being curved on different radii in eccentric relation to said pivot and having teeth thereon adapted to impart a rolling movement to the nut during the progressive compressing action of the jaws thereon as the latter are closed, and a bifurcated leaf 60 spring straddling the lug and having its bifurcated end anchored to the first mentioned lever member. 55

2. A nut cracking device comprising two lever members, one of said members having a flattened end providing a jaw thereon and the other member having a laterally curved 65 end portion forming a complementary jaw and terminating in an angularly projecting lug, a pivot pin connecting said lug with the first named jaw, the opposed edges of said jaws being curved on different radii in eccentric relation to said pivot and having teeth thereon projecting in relatively opposite directions adapted to impart a rolling 70 movement to the nut during the progressive compressing action of the jaws thereon as the latter are closed, and a bifurcated leaf 75 spring member interposed between said jaws adjacent to the pivot, the bifurcated end of 80 said spring being fixed in the first mentioned jaw, the opposite end of said spring bearing against the other jaw and freely slideable over the inner face thereof to yieldingly hold said jaws normally in spaced 85 relation to each other.

In testimony that I claim the foregoing as my invention, I have signed my name hereto.

IRVING H. GREENE.
